CATHODE-RAY TUBE SEALING APPARATUS

Walter P. Melcher and Harry H. Voelz, Chicago,
Ill., assignors to The Rauland Corporation, a
corporation of Illinois

Application December 5, 1950, Serial No. 199,239

3 Claims. (Cl. 49—1)

1

This invention relates to improved apparatus for the fabrication of cathode-ray tubes having an envelope comprising a neck portion of vitreous material such as glass or the like, a hollow flared or conical portion which may be of metal, and a window or viewing plate of glass or similar transparent material. More particularly, this invention is directed to improved apparatus for sealing the glass viewing plate to the hollow conical portion of a cathode-ray tube envelope in which these portions have a rectangular or other non-circular cross section.

In cathode-ray tubes of the metallic type, the conical portion of the envelope is usually provided with a flange or lip at one end in which the glass window is fitted for sealing purposes. To obtain a satisfactory seal it is preferable that the cone be held with its axis in a vertical position and the window be placed on its upper end in contact with the flange. Gas burners may then be directed to the underside of the flange and the assembly rotated about its axis for uniformity of heating. The heat from the burners causes the glass of the window in contact with the flange to soften and settle onto the flange, sealing the window to the conical portion.

Heretofore in the art it has been usual that cathode-ray tube envelopes be composed of a tubular neck portion, a hollow conical portion of circular section, and a circular viewing or face plate. As previously stated, the face plate may be sealed to the conical portion by placing the cone in a suitable apparatus with its large end upward and the face plate resting thereon. An array of heating elements may be positioned to surround the conical portion and directed to its upper end. Relative rotation may then be imparted between the burners and the conical portion of uniform heating.

The advent of rectangular-screen cathode-ray tubes for use in television receivers has presented a serious sealing problem. That is, it has become necessary to provide apparatus whereby heat may be applied uniformly to the sealing surface between the cone and face plate portions of a cathode-ray tube envelope when the sections of these portions are not circular. As long as these sections are circular, uniform heating may be obtained simply by arranging the heating elements in an array surrounding the cone and effecting relative rotation between the cone and the heating elements, as described above.

The present invention provides improved apparatus for effecting an efficient seal between the viewing plate and conical portion of a cath-

2

ode-ray tube envelope when these portions have a rectangular or other non-circular section; and it renders feasible the production of rectangular-screen cathode-ray tubes, particularly of the metallic type. The apparatus comprises a supporting means having a structure mounted thereon for supporting the hollow generally conical portion of a cathode-ray tube which may be composed of metal, and which may have a flanged end of a rectangular or other non-circular cross-sectional configuration. The conical portion is supported in the aforementioned structure with its flanged end upward and with the viewing plate resting thereon. A cam having a contour corresponding to the peripheral configuration of the flanged end of the cone is mounted on the supporting structure in coaxial relation with the cone in a plane parallel to the plane of the flange, and a continuous chain is supported by and encircles the cam. A plurality of gas burners are mounted on the chain extending upwardly and directed towards the underside of the flanged end of the cone. Finally, the apparatus includes a driving means for imparting relative rotational motion between the cam and chain so that the burners may follow the contour of the flanged end of the cone for uniform heating of the flange which serves as a sealing surface.

It is, accordingly, an object of this invention to provide improved apparatus for sealing the viewing plate of a cathode-ray tube to the hollow, generally conical, portion of the tube.

A more particular object of the invention is to provide improved apparatus for sealing the viewing plate of a cathode-ray tube to a hollow, generally conical, metallic portion having a flanged end, especially when the viewing plate and flange have a rectangular or other non-circular configuration.

The features of this invention which are believed to be new are set forth with particularity in the appended claims. The invention itself, however, together with further objects and advantages thereof may best be understood by reference to the following description when taken in conjunction with the accompanying drawings, in which:

Figure 1 shows one embodiment of the improved sealing apparatus of the invention, supporting various portions of a cathode-ray tube envelope which are to be sealed together.

Figure 2 shows a view of the apparatus of Figure 1 taken along the lines 2—2, but with the envelope portions removed for purposes of clarity.

Figure 3 shows a view of the apparatus taken

along the lines 3-3 of Figure 2, but with some components of the apparatus omitted to simplify this view, and,

Figure 4 represents a burner-supporting bracket as viewed along the lines 4-4 of Figure 1.

The apparatus of Figure 1 includes a supporting means or table 10 having an upwardly-extending tubular driving member 11 rotatably mounted thereon. An electrical motor is mounted 10 on a shelf 16 of the supporting table and is mechanically coupled by a belt drive 17 to a driving wheel 14 which is affixed to tubular driving member 11.

Driving member 11 has a turn-table 18 secured 15 to its upper end so that energization of motor 16 causes the turn-table to rotate. Turn-table 18 supports a plurality of upwardly-extending brackets 19 which, in turn, support a cam assembly 20 shown more clearly in Figures 2 and 3. 20 The cam assembly has a central aperture surrounded by brackets 21 which serve as a supporting means for the cone 22 of the cathode-ray tube envelope. It will be assumed that cone 22 has a flange surface 24 of rectangular cross-section at its large end for receiving a rectangular viewing plate. Moreover, it will be assumed that the small end of the cone has been previously sealed to a vitreous neck portion 23. The brackets 21 engage the cone so that the cone and the cam assembly rotate in unison as turn-table 18 is rotated. Cam assembly 20 is constructed to have a contour corresponding to the rectangular configuration of flanged end 24 of cone 22, and the cone is supported with the plane of its flanged 35 end parallel to the plane of cam 20 and in coaxial relation therewith.

A continuous chain 29 is supported by cam assembly 20 and encircles the periphery of the cam. The chain is of usual well-known construction and is composed of various links and inter-connecting transverse pins, the pins additionally acting in a manner to be described as rollers engaging a surface of cam assembly 20. The upper links of chain 29 are replaced by brackets 30, shown in Figure 4, and these brackets support an array of upwardly-extending burners 31 directed to flanged end 24 of cone 22. Burners 31 are coupled to a gas manifold 32 by means of rubber tubes 33. A pair of upwardly extending rods 34 is mounted on table 10 and the gas manifold is supported on these rods by means of collars 35 secured thereto by screws 36. Rods 34 also support a pair of resilient supporting arms 38, 39 which are mechanically coupled to the chain to prevent rotational motion thereof as the cam assembly is rotated. These resilient supporting arms are connected to rotatable collars 38a, 39a on rods 34, the rotatable collars being supported on the rods by secured collars 38b, 39b. The supporting arms are urged against chain 29 by tension springs 40, 41 (Figure 2) the tension springs being connected to the arms and to upwardly extending strips 42, 43 fixed to the gas manifold.

As shown in the section of Figure 3, cam assembly 20 may comprise a pair of plates 44, 45 spaced apart by tubular spacing members 46, 47 and held together by screws 48, 49. The peripheries of plates 44, 45 engage the roller pin portions 50, 51 of chain 29, and form what may be termed "tracks" for the chain. Moreover, the cam assembly may include a bottom plate 45a spaced from plate 45 by a plate 45b, the bottom plate acting as a support for the chain. As shown in this figure, each of the burners 31 may be se-

cured to brackets 30 by means of a threaded portion 52. The threaded portion may be screwed into a tapped hole in each bracket, or may be secured to the bracket by means of a nut on the threaded portion.

The apparatus also includes an air tube 25 mounted coaxially within tubular driving member 11 in frictional engagement therewith and extending upwardly through turn-table 18 into the neck portion 23 of the cathode-ray tube envelope. Air tube 25 projects through a rubber air seal 26 and has a small aperture 27 formed therein which acts as a bleeder. Air is introduced into the air tube through a rotary air seal 28 of well-known construction.

To perform the sealing operation, the flanged cone 22 and neck portion 23 of a cathode-ray tube envelope are placed in the aperture of cam assembly 20 and supported by brackets 21 so that the plane of the flanged end 24 of the cone is parallel to the plane of the cam assembly. Face plate 37 is then placed on the flanged end. Rubber air seal 26 is inserted into the neck portion, as shown, and electrical motor 15 is energized to rotate turn-table 18. Rotation of the turn-table causes cam assembly 20 and cone 22 to rotate in unison. Rotation of chain 29 is prevented by resilient arms 38, 39, the chain being loosely supported by the cam so that rotation of the cam causes the configuration of the chain to follow the contour of the rotating cam which, in turn, causes the burners supported by the chain to follow the contour of the flanged end of the cone. Burners 31 are ignited to heat the underside of the flange 24 and bring the flange to the sealing temperature. Air under pressure is introduced through air tube 25 into the interior of the envelope assembly to prevent the edge of viewing plate 37 from sagging during the sealing operation. Aperture 27 in the air tube allows some of this air to escape and avoids excessive pressure in the interior of the cathode-ray tube.

It is sometimes desirable to heat viewing plate 37 prior to the sealing process so that cracking will be prevented. This is accomplished by means of a burner 50 adjustably supported by one of the rods 34 so that it directs a soft flame to the upper surface of the viewing plate.

This invention provides, therefore, an improved apparatus for sealing the viewing plate of a cathode-ray tube envelope to the conical portion thereof. The apparatus may be used to perform its sealing function when the cone and viewing plate have any irregular cross-section, it being merely necessary that cam assembly 20 have a configuration corresponding to the configuration of these elements. Regardless of the configuration of these elements, the burners are caused to follow their contour and provide uniform heating around their periphery so that a satisfactory seal may be obtained. Moreover, when so desired the apparatus is readily adaptable for sealing the viewing plate to the cone of a cathode-ray tube having a circular section, it being merely necessary to provide cam 20 with a corresponding circular configuration.

While a particular embodiment of the invention has been shown and described, modifications may be made and it is intended in the appended claims to cover all such modifications as may fall within the true spirit and scope of the invention.

We claim:

1. Apparatus for sealing a viewing plate portion of a cathode-ray tube to a hollow generally

conical portion having a flanged end comprising: a supporting means; a structure mounted on said supporting means for supporting said conical portion with said flanged end upward and with said viewing plate resting thereon; a cam member having a contour corresponding to the peripheral configuration of said flanged end mounted on said structure in a plane parallel to the plane of said flanged end and in coaxial relation with said conical portion; a continuous chain 10 encircling said cam member; a plurality of heating elements supported by said chain and directed towards said flanged end of said conical portion; and driving means for imparting relative rotational motion between said cam and said chain.

2. Apparatus for sealing a viewing plate portion of a cathode-ray tube to a hollow generally conical metallic portion having a flanged end comprising: a supporting means; a structure 20 mounted on said supporting means for supporting said metallic portion with said flanged end upward and with said viewing plate resting thereon; a cam member having a contour corresponding to the peripheral configuration of said flanged end mounted on said structure in a plane parallel to the plane of said flanged end and in coaxial relation with said conical portion; a continuous chain supported by said cam and encircling the periphery thereof; resilient supporting means mechanically coupled to said chain for preventing rotational motion of said chain; a plurality of heating elements supported by said

5 chain around the periphery of said cam and directed towards said flanged end of said conical portion; and driving means coupled to said supporting structure for imparting rotational motion to said cam.

3. Apparatus for sealing a viewing plate portion of a cathode-ray tube to a hollow generally conical metallic portion having a flanged end comprising: a supporting means; a structure mounted on said supporting means for supporting said metallic portion with said flanged end upward and with said viewing plate resting thereon; a cam member having a peripheral configuration corresponding to the peripheral configuration of said flanged end mounted on said supporting structure in a plane parallel to the plane of said flanged end and in coaxial relation with said conical portion; a continuous chain supported by said cam and encircling the periphery thereof; a pair of resilient supporting arms mechanically coupled to said chain for preventing rotational motion of said chain; a plurality of upwardly-extending gas burners supported by said chain around the periphery of said cam and directed toward said flanged end of said conical portion; and driving means coupled to said supporting structure for imparting rotational motion to said cam.
